United States Patent Office.

P. S. DUSOUCHET, OF NEW ORLEANS, LOUISIANA.

Letters Patent No. 80,932, dated August 11, 1868.

IMPROVED SWITCHING-APPARATUS FOR STREET-RAILWAY CARS.

The Schedule referred to in these Letters Patent and making part of the same.

TO ALL WHOM IT MAY CONCERN:

Be it known that I, P. S. DUSOUCHET, of the city of New Orleans, parish of Orleans, and State of Louisiana, have invented a certain new, useful, and improved Apparatus to be Attached to City-Railroad Cars for switching the same from one track to another; and I do hereby declare the following to be a full, clear, and exact description of the same, reference being had to the annexed drawing, making a part of this specification.

The object of my invention is to dispense entirely with the adjustable switches that are now in general if not universal use, and thus to avoid the expense that is necessarily incident to the keeping of a man, or "switch-tender," as he is usually called, at every intersection of one railroad-track by another, or, in other words, at every point at which a single track leads or runs into two or more branches; and it consists of a rock-arm that articulates upon the fore or front axle of the car, midway between the wheels, between two fixed or immovable collars thereupon, and which is operated through the medium of chains, or their equivalents, and a lever of peculiar construction by the driver on the car.

But my invention will be better and more quickly understood by referring to the drawing, on which it is represented in perspective, as when applied to a car, (the running-gear and lower framework only of the latter being shown,) which stands on a track near its intersection by another track.

The delineation of the intersection or joining of two tracks is made in order to exhibit, in connection therewith, the fixed central short bar or rail, through the agency of which my apparatus effects the object it is designed to accomplish.

Upon the drawing, A is the rock-arm, to which I have referred in the preamble, and B B' two projecting parts, which, it will be observed, radiate from a central sleeve at right angles, or nearly so, to each other. Of these two parts, B is the arm, which effects the switching of the car from one track into another, and hence, it may properly be called the "guide-arm."

The fixed collars *aa* upon the axle hold the centre sleeve A of the rock-arm in its place, or, in other words, prevent it from having any transverse or lateral motion.

The guide-arm B should be long enough to bring its outer extremity very near without actually touching the ground, whenever it occupies a pendent or perpendicular position, and is to act upon the car and force it from one into another track.

To perform this operation, this guide-arm must bear against something that is fixed and immovable, and of such character that its action upon the arm will force it to take a direction in its onward movement that is parallel with the line of the rails on the track on which the car is to be carried. A short curved bar or rail, R, midway between the rails, at the point of intersection, as shown on the drawing, is the simplest and best device or means for fulfilling these conditions. This bar should be slightly curved at the extremity, in a reverse direction to the curve that is parallel with the rails, as shown, in order that the guide-arm, in coming into contact with it, may not strike with too sudden and violent a shock, and be led gradually into the performance of its function.

To diminish friction between the arm B and the rail R, which may in its turn be designated by the name of guide-bar, a horizontal sleeve-roller may be put upon the extremity of the former, or friction-rollers may be introduced into the rail R, along its entire length, accordingly as the one or the other expedient may be demonstrated by experience to be most effective.

An oblique brace, b, which is supported at its foot by a loose sleeve or collar, c, around the axle of the car, and bears against the arm B, near its outer end, will effectually sustain this arm against the strain to which it is subjected in the operation of switching the car, the sleeve c being of course sustained by a fixed collar on the axle. This brace, b, need not extend so near the wheel as shown on the drawing.

To elevate the arm B sufficiently to be out of the way of any object upon the road, and so as not to impinge against the rail R, unless the car is to be switched by its agency, the arm B' is provided, which being weighted, secures this end by its superior gravity over the guide-arm B. But in lieu of the weight 2, a spring may be used for the same purpose.

A chain, *d*, being secured at one of its ends to the extremity of the arm *B'*, and at its other end to a c timber of the framework of the car, as shown, prevents too low a depression of the said weighted arm for the quick raising of it at the proper time, in order to lower the extremity of the guide-arm to effect the switching of the car, whilst the chain *e*, that is attached at one of its ends to a front timber of the car, and at the other to the guide-arm *B* near its outer end, prevents said guide-arm from passing beyond a vertical line in the operation of switching, and hence, secures its certain action in that behalf.

A lever, *C*, actuates my apparatus. The long arm of this lever projects above the platform in front of the car, on which the driver stands, whilst its short arm is below said platform, and is there provided upon its rear side with a circular projection, *g*, to which a chain, *f*, is secured at one of its ends, and to the outer extremity of the weighted arm *B'* at its other, as shown on the drawing.

A backward movement of the long arm of the lever *C* winds the chain *f* upon the part *g* of its short arm, and drawing up the weighted arm *B'*, depresses the guide-arm *B* by partially revolving it, until it is stopped in a vertical position by the chain *e*, which is the true position for it to occupy in the operation of switching the car off the track on which it is running, and into the intersecting, or, more properly, the radiating or driving-track. Hence, it will be perceived that the driver can carry his car upon any track he pleases, at his own will and pleasure, without intervention or assistance from any other person, and without the use of a movable or adjustable switch.

My invention is simple and cheap, and it can be applied to every existing car, whatever may be its form or peculiarities of construction, and, in consequence of its operating from or upon the axle of the car, it is not obnoxious to the objections that obtain against those which, connected with the body of the car, have to be adjusted with reference to the elevation or depression thereof, accordingly as the number of passengers in the car happens to be greater or less.

Having thus fully described my invention, and explained its mode of operation, what I claim, and desire to secure by Letters Patent, is—

The rocker-arm *A*, when provided with the radiating guide-arm *B* and the weighted arm *B'*, in combination with the lever *C* and chains *d e f*, the whole being constructed, arranged, and operating conjointly, substantially as herein described for the purpose set forth.

P. S. DUSOUCHET.
